UNITED STATES PATENT OFFICE.

EDWARD PENGELLY, OF SAN FRANCISCO, CALIFORNIA.

CIGARETTE IGNITER.

Application filed March 1, 1926. Serial No. 21,887.

This invention relates to improvements in cigarette lighting attachments for motor vehicles of that character in which a suction is induced through the cigarette by means of the suctional force created with the operation of the engine, and the cigarette is simultaneously ignited by means of an electric heating element which obtains its current from the battery of the vehicle.

10 The present invention particularly represents an improvement over the device shown in my co-pending application for patent, Serial No. 616,906, filed February 5th, 1923, and also over the specific valve and switch structure shown in my Patent No. 1,520,887, dated December 28th, 1924.

In the previous devices the opening of the suction valve automatically caused the circuit to the heating element to be closed, regardless of the absence or presence of a suctional force in the suction line.

It was therefore possible to cause the electric element to function at any time whether the engine of the car was running or not so that if the valve was accidentally opened and left open the heating element would be heated and remain heated for the entire time the valve was open, shortening the life of the element and causing the battery to be run down if not noticed.

The principal object of the present invention therefore is to avoid the above feature by providing a switch for the heating circuit arranged to be closed only by suction; and causing the suctional force to communicate with this switch structure simultaneously with the opening of the suction to the cup engaging one end of the cigarette. Therefore if the valve is opened but no suction is in the line, the electric element will not be heated and no harm will be done.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

50 In the drawings similar characters of reference indicate corresponding parts in the several views:

Fig. 1 is a front elevation of the device

shown in connection with the preferred form of cigarette holding and dispensing means.

Fig. 2 is an end view of the apparatus.

Fig. 3 is a transverse section on the line 3—3 of Fig. 1.

Fig. 4 is a longitudinal section through the suction cup and control valve taken on the line 4—4 of Fig. 3.

Fig. 5 is a diagram of the electric circuit of the apparatus.

Referring now more particularly to the characters of reference on the drawings, the supporting structure of the device includes connected and outwardly projecting end plates 1 and 2. Longitudinally spaced and horizontally aligned cradles 3 extend between the plates 1 and 2 to support a single cigarette against transverse movement. It may here be noted that the distance between the plates 1 and 2 is intentionally made somewhat greater than the length of any standard cigarette now on the market. A frame 4 is removably supported by the plates 1 and 2 above the cradles, said frame having a cigarette receptacle 5 pivotally mounted therein. This receptacle is tilted forward on its pivot by means of a handle 6, this movement causing a single cigarette to drop from the receptacle onto the cradles. This structure, however, forms no part of the present invention and is more fully shown and described in my co-pending application on a cigarette container and dispenser filed March 22nd, 1926, Serial No. 96,441.

Located outwardly of the end plate 1 is a horizontal transversely extending sleeve 7 in which is turnably mounted a valve stem 8 having a blind bore 9 open to the inner end of the stem. A handle or knob 10 is applied to the outer end of the stem in front of the outer edge of the plate 1. The opposite end of the sleeve 7 has an opening 11 leading thereto, arranged to communicate with a tube 12 leading to a source of suction, preferably the intake manifold of the engine of the vehicle on which the device is to be mounted.

Extending at right angles to the sleeve 7 and in alignment with the cradles 3 outwardly of the plate 1 is another sleeve 13, closed at its outer end. A plunger 14 having a cup like depression 15 at one end facing the opposite plate 2 is slidable in the

sleeve 13. This plate has a passage 16 therethrough leading to the depression and constantly communicating with a passage 17 extending between the sleeves 13 and 7. 5 The stem 8 has a radial passage 18 leading from the bore 9 to the periphery of the stem and transversely aligned with the passage 17. The sleeve 13 has a longitudinal slot in its outer side to receive a pin 19 projecting radially from the plunger. The knob 10 has a plate 20 mounted in connection therewith, which plate has a recess 21 in the side thereof facing the pin 9, of a size to receive the same. This recess is of 15 such form and so disposed relative to the pin that when the knob is turned to the left, the plunger is retracted into its sleeve by engagement of the pin with the right hand end of the slot, and the outer end of 20 the passage 18 is then some distance to the left of the passage 17 as shown in Fig. 4. When the knob is turned to the right, an initial movement of the knob and stem takes place without moving the plunger. A further movement of the knob then causes the 25 plunger pin 19 to be engaged with the left hand portion of the recess, causing the plunger to be moved outwardly of the sleeve or toward the plate 2. At the same time 30 the passages 18 and 17 are placed in communication with each other. If therefore a suction is present in the tube 12 and sleeve 7, air will be drawn through the plunger from the cup end thereof, inducing a suction through a cigarette engaged 35 with the cup. The initial turning of the stem 8 without moving the plunger enables the normal spacing between the passages 18 and 17 to be quite large, preventing leakage therebetween, without having to have a large movement of the plunger, before such passage alinement takes place. This 40 enables the suction to be applied to the plunger whether long or short cigarettes are engaged without possibly buckling the cigarette to place the suction passages in alinement, since the cigarette abuts at its opposite end against an immovable heating element, as will be hereinafter described. 45 It may here be noted that the pin 19 and plate recess 21 also serve as a stop to limit the rotation of the valve stem in either direction.

Projecting upwardly from the sleeve 7 50 behind the sleeve 13 is a cylinder 22 having a piston 23 movable snugly therein. A passage 24 leads from the bottom of this cylinder to the sleeve 7, the stem 8 having a passage 25 leading from its periphery to the bore 9 in transverse alinement with the 55 passage 24 and so disposed as to communicate with said passage at the same time as the passages 17 and 18 communicate with each other. Such communication therefore 60 causes the piston 23 to be drawn down in

the cylinder, provided of course there is suctional force present in the sleeve 7. A spring 26 acts to maintain the piston 23 raised in the cylinder. Projecting into the cylinder below the piston are spaced contacts 27 insulated from each other and adapted to be engaged and bridged by a preferably flexible conducting element 28 mounted in connection with the piston 23 below the same. The element 28 is normally above the contacts, and only engages the same when the piston is lowered a certain distance by reason of a suctional force. 70

An electric heating element 29 is mounted in a casing 30 which is disposed against and outwardly of the plate 2, being removably held in position by a support 31 of suitable character, provided with said end plate. The element 29 faces an opening 32 provided in the plate 2, and is aligned with the cradles and plunger 14. The particular arrangement of parts of this element may be as shown in my Patent No. 1,538,258, dated May 19th, 1925, or otherwise as may be found desirable. 80

In wiring the contacts 27 and element 29 to a source of current, such as the battery of the car, I preferably ground one contact 27, connect the other to one end of the element 29 by a wire 33, and connect the other end of the element to the battery 34 by a wire 35. 90

In operation a cigarette is dispensed from the receptacle onto the cradles or placed thereon by hand and the knob 10 may then be rotated at any time the engine is running to cause the cigarette to be ignited. As previously stated, the knob when turned ultimately causes the cigarette to be shoved toward the right, which movement will cause it to be engaged at one end with the element 29, while the other end seats in the depression or cup of the plunger 14. 100

A suction is then induced through the plunger 14 and at the same time the circuit through the element is closed, as hereinbefore set forth. The cigarette will then be ignited and a draft induced therethrough at the same time. Owing to the fact that the suctional force controls the closing of the element switch, the cigarette will not be ignited unless the engine is running. 110

In connection with this apparatus I preferably mount an ash tray 36 below the cradles, not only for the convenience of the 120 smoker at any time, but to catch any ash which may be formed on and drop from the cigarette while it is being initially ignited.

The ash tray also prevents a lighted cigarette, if left on the supporting cradles, from falling onto the floor of the car and possibly causing a fire. 125

While it is not absolutely essential, I contemplate making the supporting structure, 130

the sleeves 7 and 13, cylinders 22 and sundry other parts of bakelite. This material is not only capable of being easily molded and worked but forms a super-insulating means 5 for the electrical contacts.

From the foregoing description it will be readily seen that I have produced such a device as substantially fulfills the objects of the invention as set forth herein.

10 While this specification sets forth in detail the present and preferred construction of the device, still in practice such deviations from such detail may be resorted to as do not form a departure from the spirit of 15 the invention, as defined by the appended claims.

Having thus described my invention what I claim as new and useful and desire to secure by Letters Patent is:

20 1. A cigarette lighting device including a normally inert ignition means adapted to engage one end of a cigarette, and suction controlled means for placing the ignition means in operation.

25 2. A cigarette lighting device including a normally inert electric ignition element adapted to engage one end of a cigarette, switch means for said element, and suction controlled means for closing said switch 30 means.

35 3. A cigarette lighting device including a normally inert electric ignition element adapted to engage one end of a cigarette, switch means for said element, a suction cup for engagement with the opposite end of the cigarette, a suction actuated means for closing the switch means, and a common valve for controlling the flow of air in said cup and switch closing means.

40 4. A cigarette lighting device including a normally inert electric ignition element adapted to engage one end of a cigarette, switch means for said element, a suction cup for engagement with the opposite end of the cigarette, and movable toward the element, a suction actuated means for closing the switch means, and a common member for controlling the flow of air in said cup and switch closing means, and the movement of 50 said cup.

55 5. A cigarette lighting device including a normally inert electric ignition element adapted to engage one end of a cigarette, switch means for said element, a suction cup for engagement with the opposite end of the cigarette, a suction actuated means for closing the switch means, a suction passage member, and a common valve for opening and closing communication between the cup and the switch closing means simultaneously.

60 6. A cigarette lighting device including a normally inert electric ignition element adapted to engage one end of a cigarette, switch means for said element, including a pair of spaced contacts, a circuit for the

element in which the contacts are interposed, and suction controlled means for bridging said contacts.

7. A cigarette lighting device including a normally inert electric ignition element 70 adapted to engage one end of a cigarette, switch means for said element, including a pair of spaced contacts, a circuit for the element in which the contacts are interposed, a cylinder in which said contacts are located, 75 a member to engage and bridge the contacts normally spaced therefrom, a piston in the cylinder fixed with said member, suction passage means connecting with the cylinder at such a point that a suctionsal force in said 80 passage means will cause the piston to move in a direction to cause the said member to engage the contacts, and a hand controlled valve in said passage means.

8. In a cigarette igniting device, an ignition element for engagement with one end of a cigarette, a suction cup for engagement with the other end of the cigarette and movable longitudinally thereof, a sleeve in which said cup is mounted, another sleeve extending 85 at right angles to said cup, said sleeve at one end being connected to a suction passage means, a stem turnable in the last named sleeve and having a blind bore communicating with said passage means, a passage 90 between said sleeves, a passage in the cup communicating constantly with said first named passage, and a passage from the bore of the stem to the periphery thereof transversely alined with the first named passage, 95 and adapted to register therewith when the stem is turned in a certain direction.

9. In a cigarette igniting device, an ignition element for engagement with one end of a cigarette, a suction cup for engagement 100 with the other end of the cigarette and movable longitudinally thereof, a sleeve in which said cup is mounted, another sleeve extending at right angles to said cup, said sleeve at one end being connected to a suction passage means, passage means between said suction passage and the cup-sleeve including a tubular valve member turnably mounted in the last named sleeve, and means between 105 said valve member and the cup for causing the latter to be moved toward the element only after a certain amount of rotation of the valve member toward a passage opening position has taken place.

10. In a cigarette igniting device, an ignition element for engagement with one end of a cigarette, a suction cup for engagement 110 with the other end of the cigarette and movable longitudinally thereof, a sleeve in which said cup is mounted, another sleeve extending at right angles to said cup, said sleeve at one end being connected to a suction passage means, passage means between said suction passage and the cup-sleeve including a tubular valve member turnably mounted 115

in the last named sleeve, a pin projecting radially from the cup, and a plate fixed with the valve member and having a recess to receive the pin, the recess being of such form 5 as to permit of a certain amount of rotation of the valve member without disturbing the pin and cup, while causing a longitudinal

movement of the pin and cup to take place with a further rotation of the valve member; the latter being arranged to prevent communication between the ends of the passage means until such further rotation is effected. 10

In testimony whereof I affix my signature.
LEWIS PENGILLY.
